PROCESS FOR COKING OIL

Alfred Fisher, Chicago, Ill., assignor to Universal Oil Products Company, Chicago, Ill., a corporation of South Dakota

Application October 2, 1931, Serial No. 566,503

6 Claims. (Cl. 202—5)

This invention relates to the treatment of hydrocarbon oils and more particularly refers to the heat treatment of oils, such as petroleum and its residues, coal tars, pitches and the like to substantially devolatilize the same and effect their reduction to coke or carbonaceous material.

Many processes for continuously coking hydrocarbon oils have been proposed, some of which utilize indirect heating of the material to be coked while others employ direct contact between said material and the heating medium. One process of the former class employs a plurality of chambers which may be externally heated or to which the material to be coked is supplied in a heated state, one of which chambers is being filled with coke while the others are being cleaned and prepared for operation. This method involves costly and cumbersome equipment and is also hazardous, due to the relatively large volume of combustible material which is ordinarily maintained in the coking zone.

Other processes of the same type employ mechanically operated scrapers or other means of loosening the carbonaceous material from the walls of the coking vessel, continuously introducing oil to the heated zone and continuously removing coke or carbonaceous material from the system. Efficient apparatus for such operations have not so far been developed, the chief obstacle being warping or distortion of the scrapers or other coke-removing devices, due to the high temperatures employed and inability to properly cool the apparatus. Methods of the type involving direct contact of the material to be coked with heating mediums such as products of combustion and other processes involving partial combustion of the materials undergoing coking are objectionable, regardless of the methods used to remove the coke from the zone of treatment and thus operate the process continuously, on account of the objectionable oxidation products formed, loss of material due to oxidation or combustion and inability to efficiently separate hydrocarbon vapors from combustion products.

The present invention offers distinct improvements to the existing art by providing a method and means of intermittent operation whereby hydrocarbon oils such as petroleum and its residues, coal tars, pitches and the like or mixtures of such oils are reduced to coke or carbonaceous material by treatment in an externally heated rotary retort. The most essential improvement of the present invention comprises intermittently arresting the coking operation and cooling the carbonaceous mass in the retort by the introduction

of steam or water onto its surface, removing from the zone of treatment the loose carbonaceous material which accumulates in the retort.

I have found that by cooling the coke or carbonaceous layer upon the walls of the retort by the introduction of water or steam onto its surface, said carbonaceous mass contracts more rapidly than the shell of the retort, thus breaking the bond therebetween and effecting removal of the carbonaceous layer. I have also found that by this method of removing the coke which adheres to the walls of the retort it normally falls away in relatively large pieces, thus minimizing the production of small coke particles or fines which predominate in many other methods of coke removal.

It is also characteristic of the operation of the present process that the temperature in the coking zone need be reduced only sufficiently to break away the adhering carbonaceous mass from the walls of the retort after which the coking operation may be continued, the total coke-removing period consuming only approximately 15%, or in some cases somewhat more, of the total operating time.

The attached drawing illustrates diagrammatically in vertical section one specific form of apparatus in which the process of the present invention may be accomplished. The drawing and the following description are given for the purpose of more clearly illustrating the novelty and features of the invention. The rotary retort is indicated in general at 1. The cylindrical shell 2 of the retort is located in a suitable furnace setting 3 and is rotated by any suitable motivating means (not shown) through gear arrangement 4. Ends 5 and 6 of the retort, located outside the heating zone of the furnace preferably are stationary and any suitable form of packing arrangement (not shown) is provided between the rotary shell 2 and stationary ends 5 and 6 to prevent escape of materials from the retort.

Any suitable fuel such as oil, gas, pulverized solid fuel or the like is supplied to combustion zone 7 of the furnace by means of any suitable burner (not shown) through burner port 8. The hot combustion gases pass upward through the perforated arch 9 of the furnace, along shell 2 of the retort through heating zone 10 and out of the furnace to a suitable stack (not shown) through flue opening 11.

The retort is provided with any suitable feeding arrangement such as, for example, a perforated feed pipe 12 traversing the length of the retort into which the material to be coked is introduced

through line 13 and valve 14 to be sprayed onto the heated walls of the retort through suitable perforations 15. Preferably, the size and spacing of perforations 15 are such that a substantially 5 uniform quantity of charging material is supplied to all portions of the inner surface of shell 2. By rotation of shell 2 it is substantially uniformly heated around its entire circumference and by such heating the material sprayed against the 10 walls of shell 2 is substantially devolatilized and reduced to coke or carbonaceous residue.

Preferably the form and size of perforations 15 is such that the charging material is sprayed against the walls of the retort in a somewhat 15 atomized form and, to prevent plugging of perforations 15, steam may be intermittently supplied to charging line 12 through line 16 and valve 17, the flow of oil through valve 14 preferably being stopped during said intermittent steaming 20 operations.

As a layer of coke or carbonaceous material builds up upon the inner surface of shell 2, the poor heat conductivity of the carbonaceous material will reduce the flow of heat from the furnace to the material undergoing coking. To offset this reduction in the rate of heat transfer the furnace temperature preferably is gradually increased during the coking operation. The 25 heated shell 2 of the retort is preferably constructed of a suitable metallic alloy such as nickel chromium steel capable of withstanding the relatively high temperatures to which the shell of the retort is subjected.

After a substantial layer of coke has been built 30 up upon the inner surface of revolving shell 2 of the retort the supply of charging stock to the zone of treatment is stopped. Preferably, heating of the retort is continued for a time after the feed is discontinued to substantially vaporize any volatile matter remaining on the surface of the coke 35 layer. Firing is then discontinued or substantially diminished and water or steam introduced to feed line 12 through line 16 and valve 17 is sprayed through perforations 15 upon the surface 40 of the bed of coke, the rotation of the retort being preferably continued during this operation. By this method the coke is cooled and contracts more rapidly than shell 2 of the retort, thus breaking the bond between the metal shell and the carbonaceous layer. The coke cracks and scales 45 away from the walls of the retort in relatively large pieces and passes to the discharge end 6 of the retort, assisted by the continued rotation of shell 2 and the slight inclination of the retort 50 from the horizontal toward its discharge end 6. The stationary discharge end of the retort is provided with a coke discharge tube 18 and an outlet line 21, containing valve 22, for vapors and gases. The lower end of coke discharge tube 18 is preferably 55 immersed in liquid which acts as a seal to prevent the escape of vapors and gases through this port.

Any suitable liquid, such as oil or water, may be employed, and may serve also as a quenching 60 medium for the coke. Coke may be discharged during the intermittent cleaning operation of the retort into a continuous conveyor 19 of any suitable form, one end of which is immersed in the liquid seal and quenching chamber 20 and by means 65 of which the coke may be removed to storage or elsewhere, as desired. Vapors removed from the retort through line 21 and valve 22 may pass to fractionation, condensation, cooling and collection apparatus or to any other desired treatment, means for which are well known and are 70

not shown in the drawing. If desired, the heavy portions of the vapors may be separated from the lighter portions by fractionation and returned to the retort for further treatment together with the charging stock by well known means (not 80 shown).

Preferably, the process is operated at substantially atmospheric pressure although relatively low superatmospheric pressures or partial vacuum may be employed, if desired. Coking temperatures employed, i. e., temperatures to which the oil is subjected during the coking operation, may range from 900 to 1300° F., more or less, depending primarily upon the type of material being treated and the desired volatility of the coke produced as well as the desired characteristics of the other products of the process. Preferably, the temperature of the carbonaceous mass is reduced by from 300 to 600° F., more or less, by spraying it with water or steam during the scaling or coke-removing period of the operation. 95

As a specific example of the operation of the process of the present invention, a residual oil resulting from cracking, which contains about 23.7% of coke by laboratory distillation analysis, 100 is supplied to the externally heated rotary retort at a rate of about 1500 pounds per hour. The furnace temperature, i. e., the temperature measured in the heating zone of the furnace adjacent to but outside of the rotary shell of the retort, is 105 about 1200° F. when the feed of oil to the retort is started and is increased over about a four hour period to approximately 1800° F. This temperature is then maintained for about four hours, during which time the feed rate is gradually decreased from approximately 1500 to about 500 pounds of oil per hour. During this eight hour period the oil is continuously sprayed into the 110 coking zone for approximately 10 minutes and the 10 minute charging periods are interrupted 115 by about one-half minute periods during which steam is passed through the perforations in the charging line to prevent their plugging.

After about eight hours of operation the supply 120 of oil to the retort is stopped and firing is continued for approximately 20 minutes after which the fires are diminished, but not entirely extinguished, and water is sprayed onto the surface of the layer of carbonaceous material which has 125 accumulated on the shell of the retort. In this manner the temperature in the retort is reduced by about 400° F. over a period of approximately one hour, during which time substantially all of the coke or carbonaceous material will have scaled 130 away from the walls of the retort, being removed from the discharge end thereof. The injection of water is then stopped, the firing is increased and charging of oil to the retort is resumed at the rate of approximately 1500 pounds per hour 135 and the operation progresses substantially the same as before. The evolved vapors and gases are continuously withdrawn from the discharge end of the retort during the coking operation to condensation, cooling and collection apparatus 140 and during the cooling and cleaning operation steam and other gases from the retort are wasted.

An operation such as above outlined may yield about 18% of petroleum coke having a volatile content of less than 5%. The total liquid recovered from such an operation may be 75% to 80% of the total charge, 20% to 25% being chargeable to gas and operating loss. In this manner the cracked residual oil is substantially freed of carbonaceous material and by the same opera- 145 150

tion a gas of high calorific value and a carbonaceous fuel are produced.

It will be understood that the operation above outlined is given only for the purpose of illustration. It is only one of the many operations possible with the process of the present invention and is not intended as a limitation thereon.

The word "water" as used in the claims is intended to include water in liquid or in heated vaporous form.

I claim as my invention:

1. A continuous process for coking hydrocarbon oil, which comprises feeding hydrocarbon oil to be cracked into an externally heated rotating retort where it is subjected to a temperature sufficiently high to reduce said oil to coke, introducing steam into said retort whereby clogging of said oil feed is prevented, intermittently interrupting said oil feed and feeding water to said retort whereby to loosen and dislodge coke formed on the wall of said retort, removing said dislodged coke, and separately removing any vapors volatilizing in said retort.

2. A process for the continuous coking of hydrocarbon oil, which comprises feeding hydrocarbon oil to an externally heated rotating retort, introducing steam into said retort whereby clogging of said oil feed is prevented, subjecting said oil to a temperature sufficiently high to reduce same to coke, intermittently interrupting the feed of oil to said retort and during said period of interrupted feed of oil, feeding water to said retort whereby to dislodge coke accumulated on the inner wall of said retort, removing said dislodged coke from the retort, and separately removing vapors from said retort.

3. A process for the continuous coking of hydrocarbon oil, which comprises feeding hydrocarbon oil to be cracked into a rotating retort, introducing steam into said retort whereby clogging of said oil feed is prevented, externally heating said retort whereby said oil is raised to a temperature at which it is reduced to coke, interrupting the feed of said oil and in its stead

feeding water to said retort to dislodge the coke accumulated on the inner wall of said retort, removing said coke from said retort and collecting same, separately removing vapors volatilizing in said retort, and intermittently feeding oil and water to said retort without interrupting the rotation of said retort.

4. A process for coking hydrocarbon oil, which comprises feeding hydrocarbon oil upon the inner surface of a rotating retort, externally heating the rotating retort, while feeding said hydrocarbon oil, to a temperature sufficiently high to reduce said oil to coke, intermittently interrupting the feeding of said oil and feeding water to said retort to loosen and dislodge the coke formed on the wall of said retort, removing said dislodged coke from the retort, and separately removing vapors from said retort.

5. A process for coking hydrocarbon oil which comprises spraying hydrocarbon oil upon the inner surface of a rotating retort, and upon the surface of coke formed thereon, externally heating the rotating retort, while spraying said hydrocarbon oil, to a temperature sufficiently high to reduce said oil to coke, intermittently interrupting the feeding of said oil and spraying water upon the surface of the coke accumulated in the inner surface of the retort whereby to dislodge said coke, removing said dislodged coke from the retort, and separately removing vapors from said retort.

6. A continuous process for coking hydrocarbon oil, which comprises, spraying said oil to the internal walls of an externally heated rotating retort whereby a film of coke is formed upon said walls, intermittently interrupting the feed of oil for a relatively short period and passing steam through said oil feed to prevent clogging of the same, intermittently interrupting the feed of oil for a relatively longer period, and spraying water upon the film of coke to dislodge the same from the walls of the retort, and removing said dislodged coke and vapors from said retort.
